SHOEMAKING

Paul A. Phillips, Haverhill, Mass.

Application February 25, 1942, Serial No. 432,298

2 Claims.

(Cl. 12—146)

This invention consists in an improved process of manufacturing shoes and relates particularly to the fitting and finishing of the uppers of women's fine shoes and pumps.

Heretofore it has been the general practice in manufacturing such shoes to bind the top edge of the outer part of the upper by itself and before trimming and stitching the lining in place, that is, the binding has been folded about the raw edge of the outer part and attached to its inner marginal surface. Subsequently the folded inner portion of the binding has been covered by the lining of the shoe. The lining is often cut larger than the outer part so that on the last it projects above the top edge of the upper about the opening of the shoe, particularly about the counter portion of the shoe. The lining and upper are then secured together by a top-stitching operation in which the projecting margin of the lining is progressively under-trimmed. In these top-stitching and under-trimming operations, which are carried out after the vamp has been closed by sewing its rear ends together, there is always danger of puckering the top edge of the shoe since the lining and outer parts are likely to stretch differently and the operator may deliberately pucker the lining to make it fit. Moreover, since the top-stitching and under-trimming operations are performed on the closed upper they require considerable skill and can not be performed as conveniently and rapidly as a flat fitting operation.

The object of the present invention is to overcome the objections of the commercial process above outlined. To this end an important feature of the invention consists in simultaneously dieing out the opening of the upper in both parts of the upper, for example, the throat of a vamp and its lining, stitching a binding to the raw top edge of the lined vamp, that is, stitching it through both the vamp and its lining, and then, instead of securing the binding to the outer part of the upper only, folding the binding over the registered raw edges of both the outer and lining portions of the vamp and upon the inner face of the lining. Finally the folded binding is stitched through the enclosed vamp and lining, preferably by zig-zag stitching, and the upper thus completed by the same stitching which secures the folded binding in place. This procedure not only entirely eliminates the top-stitching and under-trimming operations and so materially reduces the cost of manufacture, but it also improves the quality of the resulting shoe by eliminating any danger of puckering of either the lining or the outer part of the upper. It also eliminates the operation of pulling the lining down about the last and so improves the side lasting of the shoe. It is further advantageous in that it increases the number of flat fitting operations in

the shoe-making method and correspondingly decreases the number of fitting operations which must be performed on the closed upper.

As an optional feature of the invention I contemplate uniting the outer and lining portions of the vamp by transverse lines of stitching which may, if desired, definitely define a counter pocket in the rear portion of the closed vamp and limit the cemented area in the vamp. These lines of stitching, or any other convenient lines of stitching, are made with the upper in flat condition before cutting out the throat opening and so under the most favorable conditions. By this stitching, not only is the counter pocket accurately and conveniently provided for, but the vamp and its lining are maintained positively united in position with their top edges accurately registering so that the operations of applying and folding the binding may be performed with assurance of accuracy, and with no danger of displacement of the parts and the upper.

These and other features of the invention will be best understood and appreciated from the following description of a preferred manner of practising it, in connection with the accompanying drawing illustrating one type of shoe in the manufacture of which my improved process may be advantageously utilized. In the accompanying drawing,

Figs. 1 and 2 are plan views of the outer and lining portions of a vamp.

Fig. 3 is a plan view showing the lining as assembled upon the outer portion of the vamp in inverted position.

Fig. 4 is a plan view of these portions in superposed relation, right side up, after the throat opening has been formed therein.

Fig. 5 is a fragmentary view in perspective showing the binding as it is preliminarily stitched to the outer top edge of the lined vamp,

Fig. 6 is a corresponding view illustrating the binding as completely stitched in the position it occupies in the finished shoe,

Fig. 7 is a fragmentary sectional view corresponding to Fig. 6, and

Fig. 8 is a fragmentary sectional view illustrating an alternative construction of binding.

The vamp blank 10 as shown in Fig. 1 may be cut or die from any material desired in the shoe to be manufactured, as for example, gabardine, suede, kid, or other upper leather or fabric. This blank is cut from such sheet stock to the outline of the desired vamp exclusive of the throat opening.

The lining blank 11 is simultaneously cut from lining material or, as in the illustrated instance, it may comprise a composite blank in which the forepart 11 is faille or other fine fabric supplemented by a doubler or plumper 12 and rear or counter sections 13 of non-slip suede. The

plumper 12 is of heavy lining material and is cemented to the face of the faille blank which is to be concealed in the finished shoe. As herein shown in Figs. 2 and 4 the forward edge of the plumper extends across the lining at about one-third of the distance from the rear end to the toe. The suede sections 13 are stitched to the rear edge of the superposed faille and plumper by a line of stitching 16. The composite lining blank corresponds in contour to the vamp blank 10 except that it is slightly shorter as shown in Fig. 3.

Having prepared the vamp and lining blanks as above explained, they are assembled in superposed relation with the lining uppermost as shown in Fig. 3 and positively united by a transverse line of stitching 14 which follows substantially the forward edge of the plumper 12. The two blanks 10 and 11 are cemented in face-to-face contact in advance of the stitched line 14, the latter forming a convenient barrier for limiting and defining the cemented area. The stitched line 14 also constitutes means for positively uniting the vamp and its lining and maintaining them accurately in the proper position.

Having thus united the two blanks the next operation consists in cutting or dieing out the throat opening 15. As suggested in Fig. 4, this is effected simultaneously or at a single operation, while the lined vamp is maintained in a flat condition. The portion removed includes part of the stitched line 14 and part of the stitched lines 16 which extend transversely either across or in the area of the throat opening. The edges formed in this cutting-out operation are raw edges, and are, of course, left accurately superposed in registration and are maintained in that relation by the cement and the stitching 14.

The lined vamp is next closed by the closing step which makes an endless closed band of the top edge of the vamp, and then the binding strip 17 is secured by a line of stitching 18 to the outer face of the upper edge of the lined vamp as suggested in Fig. 5. The binding strip 17 may be what is known as French binding, or a French cord binding, or any other desired type of binding in thin ribbon form. It is stitched wrong side out along its upper edge, and at this stage of manufacture is otherwise loose.

The next step consists in folding the binding strip inwardly over the raw top edges of both the vamp and lining and laying it in contact with the inner surface of the lining 11 as suggested in Fig. 7. In this operation the inner face of the binding is rendered adhesive either by cement applied just prior to the folding step, or, in some cases it is supplied with a normally adhesive surface, but in any case when once folded in the position shown in Fig. 7 it will remain there temporarily at least. The final step of the process consists in forming a line of zig-zag stitching 19 extending through the vamp 10, the lining 11, and the binding strip 17, thus permanently securing these parts together and finishing the top edge of the shoe or pump. Upon the outer surface of the vamp the zig-zag stitching 19 appears merely as an ornamental feature, while inside the upper the zig-zag stitching substantially covers the inner face of the binding 17.

An additional and optional step may be carried out if desired, as shown in Fig. 8. This consists in adding an elastic strip 20 to the inner face of the binding 17 and securing this additional strip in place by the same zig-zag stitch-

ing 19 already described. Such an expedient is desirable in causing the top of the shoe to cling to the foot of the wearer and to obviate any tendency of stretching.

5. It will be seen that the raw top edges of the vamp and its lining, formed simultaneously as indicated in Fig. 4, are finished by being simultaneously enclosed beneath the binding 17 and that there is accordingly no necessity for any undertrimming operation in respect to the lining, where the process of my invention is practiced.

The process of my invention has been described as being carried out in connection with a full lining, but it has the same advantages when applied to the manufacture of shoes in which a counter lining only is used or in which the counter lining only has been top stitched. The operation of smoothly placing and top stitching a counter lining has had particular difficulties heretofore, and such a lining has been particularly liable to be puckered by the operator. All of these difficulties are obviated in accordance with the process of my invention; a perfectly smooth counter lining is secured as well as a top edge having a superior binding finish.

I prefer to secure permanently the binding by a zig-zag line of stitching, but it will be understood that any pattern of stitching which substantially covers the area of the folded portion of the binding would be the full equivalent, and that the pattern of stitching applied may be adapted to the particular style of shoe being manufactured.

35. Having thus disclosed my invention and described a preferred manner of carrying it out, I claim as new and desire to secure by Letters Patent,

1. The process of shoemaking which includes 40 the steps of preparing vamp and lining blanks, uniting the two blanks by a transverse line of stitching defining the counter portions of the vamp and thereby positively and accurately fixing the blanks in the exact relationship they are to occupy in the finished shoe, cementing the blanks together forwardly of the said line of stitching, simultaneously dieing out the throat portion of the united blanks and thus accurately aligning with each other the raw edges of both the vamp and lining blanks, closing the lined vamp, thereby making its top raw edge into a closed endless band, then enclosing said raw edge by a binding folded over the inner surface of the lining, and finally zig-zag stitching through the binding.

55. 2. The process of making women's shoes without an undertrimming operation, which includes the steps of preparing vamp and lining blanks, uniting the two blanks by a transverse line of stitching defining the counter portion of the vamp and thereby positively and accurately fixing the blanks in the exact relationship occupied by them in the finished shoe, cementing the blanks together forwardly of said stitch line, simultaneously dieing out the throat portion of the united blanks and thus accurately aligning with each other the raw edges of both the vamp and lining blanks, closing the lined vamp thereby making its top raw edge into a closed endless band, then enclosing said raw edge by a binding sewn through both vamp and lining and folded over upon the inner surface of the lining, and finally fastening the folded binding inside the lining.
